US0D1038519S

(12) **United States Design Patent** (10) Patent No.: **US D1,038,519 S**
(45) Date of Patent: ** Aug. 6, 2024

(54) **HAIR DRYER**

(71) Applicant: **BELJING XIAOMI MOBILE SOFTWARE CO., LTD.**, Beijing (CN)
(72) Inventors: **Mengling Yu**, Beijing (CN); **Ningning Li**, Beijing (CN); **Ya-Ting Hsu**, Beijing (CN)

(**) Term: **15 Years**

(21) Appl. No.: **35/515,846**

(22) Filed: **Jun. 23, 2022**

(80) **Hague Agreement Data**

Int. Filing Date: **Jun. 23, 2022**

Int. Reg. No.: **DM/224566**

Int. Reg. Date: **Jun. 23, 2022**

Int. Reg. Pub. Date: **Dec. 23, 2022**

(30) **Foreign Application Priority Data**

Dec. 31, 2021 (CN) 202130883384.7

(51) **LOC (14) Cl.** **28-03**

(52) **U.S. Cl.**

USPC **D28/13; D28/35**
